UNITED STATES PATENT OFFICE.

GEORGE JOHNSTON, OF MANCHESTER, ENGLAND.

CRUSHING ROLL.

Application filed March 14, 1923. Serial No. 625,060.

To all whom it may concern:

Be it known that I, GEORGE JOHNSTON, a British subject, and a resident of Manchester, England, have invented a certain 5 new and useful Improved Crushing Roll, of which the following is the specification.

The invention has for its object to provide for crushing mills and the like, and for other kindred purposes in which massive 10 and weighty single piece rollers or cylinders have been used, a demountable roll which while possessing the requisite sturdiness, stiffness and resistance is separable for transport into a number of parts none of 15 which weighs in excess of the moderate figure of a single load for mule or other transport in inaccessible regions.

A roll or the like made according to the invention comprises essentially two shells 20 externally cylindrical and internally conical and adapted to be secured coaxially together by any convenient means with their lesser internal peripheries adjoining. The shells are internally reinforced by a series 25 of annular discs conical counterpartly to the interiors of the shells on their peripheries. These discs are drawn towards one another in opposite pairs within the shells by bolts or the like with or without springs in 30 compression on them.

A central shaft is provided and the discs may form a driving connection between this and the shells or separate discs, or spiders 35 may connect the shells (for example, an inward flange or flanges on them) with the shaft (for example a peripheral flange on it).

It is found that with an adequate number 40 of discs, shells adequate in strength when reinforced by them may be made sufficiently light for the purposes set forth even in the case of comparatively large rolls.

An example of the improved construction 45 is shown on three accompanying sheets of drawings, Figure 1 being a sectional side elevation (with the reinforcing discs partly in section and partly in elevation) while Figure 2 is a front elevation and Figure 3 a sectional elevation of a detail.

In this example, the externally cylindrical internally conical roll-forming shells A, B are provided with inward flanges A¹, B¹, by which they are initially secured together. 50 These flanges also serve to connect the shells with a flange C¹ on a shaft C, discs D being fitted between the inner peripheries of the

shells and the periphery of the shaft for this purpose, and the whole being secured together by bolts D¹ and keys D².

In addition to these discs D, which as 60 well as making driving connection between shells and shaft serve as reinforcing means, there are six discs E, F, G, H, J, K, arranged outside the discs D. The discs G and K are connected by bolts G¹, K¹ to the opposite discs D, and the discs F and J to the discs H and E by bolts F¹ and J¹. As will be seen more clearly in Figure 3, 65 springs L are arranged in each case between the nuts L¹ and one of the discs, while apertures are provided in the outer discs for access to the bolts in the inner discs.

What I claim is:

1. A built-up roll for the purposes set forth comprising two shells externally cylindrical and internally conical secured together coaxially, in combination with means for securing the roll upon a shaft and means for internally reinforcing the shells comprising a series of pairs of annular discs 75 counterpartly conical on their peripheries and drawn together in pairs.

2. A built-up roll for the purposes set forth comprising two shells externally cylindrical and internally conical, inturned 85 flanges thereon, a shaft having a flange thereon, and discs secured to the shell flanges and to the flange on the shaft, in combination with a series of pairs of discs internally reinforcing the shells, and means for securing the discs in place in opposite pairs.

3. A built-up roll for the purposes set forth comprising two shells externally cylindrical and internally conical secured together coaxially, a central shaft and means 95 for securing the roll thereon, in combination with a series of pairs of discs reinforcing the shells, and bolts securing each pair together independently of the other pairs.

4. A built-up roll for the purposes set 100 forth comprising two shells externally cylindrical and internally conical secured coaxially together, a series of pairs of discs reinforcing the shells, bolts securing each pair of discs together, springs in compression between the bolts and the discs, a central shaft and means for securing the roll thereon.

In testimony whereof I have signed my name to this specification.

GEORGE JOHNSTON.
